UNITED STATES PATENT OFFICE.

DAVID M. WENGER, OF LEOLA, PENNSYLVANIA.

SWINGING WRINGER SUPPORT AND GEAR HOUSING.

Application filed July 2, 1927. Serial No. 203,191.

This application is a continuation in part of the application on Serial No. 117,114 filed June 19th, 1926, and has for its prime object the provision of improvements in swinging mechanism for supporting washing machine wringers, particularly in the means for providing a swinging housing for the mechanism imparting forward and reverse motion to the wringer rolls in any of the multiple positions provided by the swinging mechanism.

An object of this invention is to provide a longitudinal one-piece tubular swinging housing containing suitable mechanism for operating the wringer, the tubular housing being provided with a locking means adapted to prevent the housing from a swinging movement but allow the free and full rotation of the driving shafts and mechanism for operating the wringer at all times.

A further object of this invention is to provide a longitudinal one-piece tubular housing constructed of a plurality of parts which may be easily assembled into interlocked relationship by means of bolts or otherwise.

In this invention, the entire housing, within which are located the vertical shaft and horizontal shaft to drive the wringer, as well as the necessary gearing, is made up of approximately a tubular hollow casing adapted to swing circuitously in either direction on suitable supporting brackets, the reversing gearing preferably of the two tooth-faced element being fastened to an extended portion of the vertical shaft.

A further object of this invention is to provide a locking mechanism suitably fastened to a washing machine element and adapted to engage with a gear or ratchet fixed on the swinging mechanism in such a manner that the locking mechanism does not move with the swinging mechanism.

Another object of this invention is to provide a longitudinal one-piece oscillatory wringer support and gear housing which is adapted to be held in operable relationship to the main body portion of the washing machine by means of suitable bearing brackets and supporting elements rigidly attached to the main body portion, the locking mechanism being also attached thereto.

Other objects of this invention will appear from the following detailed description and as disclosed in the two sheets of drawings

which are herewith made a part of this application.

In the drawings, Figure 1 illustrates a front elevational view of the swinging reversible mechanism for supporting and operating the washing machine wringer in assembled relationship with a tub, a section of the tubular housing being removed in order to disclose the driving mechanism for operating the wringer.

Figure 2 represents a top plan view of the tubular housing showing the extension arm adapted for connection with the wringer.

Figure 3 illustrates a front elevational view of a modification of this invention disclosing a portion of the tubular housing broken away and the interlocking mechanism in assembled relationship thereto.

Figure 4 represents an end view of the extension arm or receiving the wringer.

Figure 5 illustrates a sectional view of the tubular housing taken along line 5—5 of Figure 3 and disclosing the means for securely connecting the longitudinal one-piece tubular portions together.

Figure 6 represents a sectional view of the tubular housing taken along line 6—6 of Figure 3 and showing the locking mechanism in interlocked relationship with the ratchet on the tubular housing.

Numeral 1 designates an electric motor mounted on a suitable support below a tub 2, of the washing machine, the bottom line of the tub being designated by the numeral 3. The motor 1 is adapted to be brought into driving engagement with a two-faced mitred gear 4 which is suitably attached to a vertical driving shaft 5 at its lower end directly underneath a supporting bracket 6. On the shaft 5 at its upper end is adapted to be mounted a mitred gear 7 which engages with a mitred gear 8 which is keyed to a shaft element 9. The shafts 5 and 9, according to this invention, are enclosed in a housing 10, which is supported by various means such as, near the top, by a suitable collar portion 11, integrally extended or otherwise from the bracket 12 and, at the bottom of the housing, by a gear element 13 suitably fastened to the housing which is in turn supported on brackets 6, the gear 4 and bracket 6 and shaft 5 being adapted to keep the housing 10 from shifting upward; the housing, according to this modification of the invention, is primarily sup-

ported at the bottom in a pocket formed in the supporting bracket 6. The shaft 5 is preferably journaled in a bearing element 14 near the top of the housing 10 and in a suitable bearing portion 15 near the bottom of the housing. The shaft element 9 is preferably journaled in bearings in the right angle arm portion 16 of the housing 10 and is connected to the shaft of the wringer by a suitable coupling element 17.

In the modification of the invention disclosed in Figure 1, the gear element 13 is fixed to the housing 10 near its lower end and engages with a locking gear element 18 which is adapted to be locked or released by the engagement and disengagement with a pawl 19 actuated by a lever arm 20. The object of this construction is to permit the housing 10 and arm portion 16 thereof, with all its attachments, to be swung in either direction into any position relative to the machine on which it is supported by means of brackets 12 and 6, by a simple disengagement of the pawl element 19 from the gearing 18.

In order to reverse the direction of movement of the shafts 5 and 9 through the two-faced gear 4, a suitable driving mechanism is provided between the driving motor 1 and the gear element 4, preferably as disclosed in Figure 1 and claimed in this applicant's pending application. The housing 10 and its integrally extended arm portion 16 is formed to properly receive therein the shaft elements 5 and 9 and the gears 7 and 8 and may be constructed either of a plurality of longitudinal one-piece sections securely clamped together by means of suitable fastening elements or may be formed from one integral piece as may be desired, thereby providing a longitudinal one-piece housing which may be swung circuitously to the right or left and locked in any desired position.

In the modification of this invention disclosed in Figures 3, 4, 5, and 6, the bearing elements within the housing 21, as at 22, 23 and 24, are preferably cast integrally with either one of the portions which comprise the housing 21 or otherwise as may be desired. The housing 21 is provided with an integrally extending arm portion 27, and is so constructed that it may properly receive therein driving shaft elements 28 and 29 and the gears 7 and 8. The housing 21 and 27 is preferably made, according to this invention, in two longitudinal one-piece sections 26 and 30 having overlapping joints 31 which may be securely locked or connected together by means of suitable fastening elements 32.

The housing member, in this invention, comprising the portions 21 and 27, is adapted to pivot or swing upon a bracket portion 33 securely fastened to the main body section of the apparatus by means of machine screws or otherwise as at 34 and is held in revoluble vertical position by means of an extended

bracket element 34 fastened to the main body portion of the machine by means of suitable fastening elements 35. The lower end of the housing portion 21 may be provided with a bearing section similar to the bearing portions 23 and 24, integrally connected with the housing or otherwise, in order to maintain the shaft element 28 in proper alignment. The supporting bracket 33 will keep the housing from slipping down, while the two-faced gear 75 adapted to be located at the lower end of the shaft element 28 together with the bracket 6 and shaft 5 will keep the housing from moving up.

The locking means for retaining the housing in a desired position in the modification of the invention as disclosed in Figure 6 comprises a flange element 36 having a plurality of notches 37, 38, 39 and 40 arranged peripherally thereof, the flange element 36 being securely fixed by means of set screws 41 or otherwise to the housing portion 21. A co-operating interlocking element 42 is arranged in slidable position within the bracket portion 33 in such a manner that when a notched portion 43 in the sliding member 42 is directly opposite the flange member extension 36, the housing 21 and 27 may be easily revolved into a desired position, and when the notched portion 43 is out of alignment with the flange portion 36, the sliding member 42 will be drawn by spring into one of the notched elements 37, 38, 39 and 40 in the flange member 36, thereby securely locking the housing in the desired position. In order to accelerate the sliding movement of the member 42, a suitable handle portion 44 is connected thereto and extends to a convenient position for manually operating as at 45, the rod 44 being slidably arranged in guide or bracket portions attached to the main body of the machine. In order to aid in pulling or drawing member 42 into engagement with notches 37, 38, 39 and 40, a spring 49 is positioned preferably under the bracket 34.

Figure 5 discloses one form of bringing the two longitudinal one-piece portions of the housing into interlocked relationship consisting of a cap lug portion 46 on the inner periphery of one of the housing portions, the lug portions being adapted to receive the cap screws 32 through the other portion of the housing at a countersunk section 47, thereby providing means for securely fastening the housing portions together and forming a right angle tubular container for the shaft elements 28 and 29 and gears 7 and 8. The housing locking device as disclosed in Figure 3 is preferred to the arrangement shown in Figure 2, although substitutions and alterations to the locking device, within the scope of the appended claim, will not affect the merits of this invention.

Figure 4 discloses a front view of the face plate 48, preferably integrally formed with

the arm portions 27 of the housing and is adapted to have securely fastened thereto the wringer.

The shaft 28 is extended below the bracket portion 33 a sufficient distance to allow for the two-faced element disclosed in Figure 2 and claimed in the parent case of which this is a continuation in part.

In operation, this invention will provide an efficient and inexpensive means for swinging the wringer to the right or left and lock it in a desired position, the wringer in this invention being attached to the pivotally mounted housing, while the driving shafts and gears 15 therein are arranged to receive a reversing motion through suitable gearings attached thereto.

This invention provides a convenient and simplified construction of a support for clothes wringers and a housing for the vertical and horizontal shafts including their engaging gears. One of the prime advantages is, in the provision of a rotative right angular housing having internally located bearings 25 for the shafts thereby forming a continuous encasement for the shafts, the mating gears being located within the encasement, the wringer being connected at the end of an arm portion extending integrally from the encasement, resulting in providing a rotative unit.

This invention also provides means for locking the rotative unit and for operating and reversing the wringer, the means being fixed in relationship to the housing or rotative unit, thereby resulting in the great advantage and 35 convenience of allowing the operator of the machine to remain in the same position.

The construction of the device, according to this invention, provides a rotative unit having a plurality of connected sections, simple, 40 convenient and economical to manufacture.

It is to be understood that changes, within the scope of the specification and claim, may be made without departing from the spirit of the invention.

What I claim is:—

In a device of the character described, a main body portion, a wringer support mounted thereon consisting of one piece, right angular portions fastened together into a continuous member, one right angular portion having an attaching means for connection with a wringer, another right angular portion having means for allowing the wringer support to be locked against rotation, and means mounted on the main body portion and continuous member for locking the continuous member in fixed position.

In testimony whereof I affix my signature.

DAVID M. WENGER.
